(57) **CLAIM**

The ornamental design for a patient table, as shown and described.

DESCRIPTION

FIG. 1 is a front view of a patient table showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view taken generally from the upper, front, right-hand side thereof;

FIG. 8 is a perspective view taken generally from the upper, back, left-hand side thereof; and,

FIG. 9 is a perspective view of the patient table taken generally from the upper, front, right-hand side thereof showing the table surface in an alternative lateral position and the table base in a retracted position to place the table surface at an alternative height.

The broken lines shown in the drawings depict portions of the patient table that form no part of the claimed design.

1 Claim, 8 Drawing Sheets
